UNITED STATES PATENT OFFICE.

CHARLES BARRETT, OF NEW YORK, N. Y.

ELECTRIC SEALING DEVICE.

1,386,305.

Specification of Letters Patent. Patented Aug. 2, 1921.

Application filed September 1, 1920. Serial No. 407,464.

To all whom it may concern:

Be it known that I, CHARLES BARRETT, a citizen of the United States, and a resident of the city, county, and State of New York, have invented certain new and useful Improvements in Electric Sealing Devices, of which the following is a specification.

This invention relates to machines for applying sealing wax or like material to envelopes or other articles and impressing a suitable seal on said material while it is plastic. The object of the invention is to provide a strong, reliably operating device of this character of simple construction and 15 handled with ease to produce a large number of sealing impressions in quick succession.

A preferred embodiment of my invention is illustrated by the accompanying drawings, in which Figure 1 is a front elevation 20 of the improved seal press; Figs. 2 and 3 are side elevations thereof, with parts in section, showing the device in two different positions; Figs. 4 and 5 are vertical sections on line 4—4 and 5—5 respectively of Fig. 1; and Figs. 6 and 7 are horizontal sections on lines 6—6 and 7—7 respectively of Fig. 2.

The improved seal press comprises a frame with a base 10, which may be perforated as at 10', Figs. 4 and 7, two standards 11 connected by a transverse top member 12, and a central guide rod 13 extending upwardly from said member, and secured thereto, say by screwing the reduced end 35 13' to said top member. On said rod 13 is adapted to slide vertically a handle 14 having an appropriate recess 14', a washer 15 located at the lower opening of said recess, and lateral vertical rods 16 mounted 40 to slide through suitable openings in the top member 12. The lower ends of the rods 16 are secured to the top member 17 of a carrier which also comprises parallel side members 18 lying adjacent to the standards 45 11, on the inside thereof. To these side members is secured rigidly the sealing wax receptacle 19, the wall of which preferably contains an electric heater of any approved construction, indicated at 20, to which current 50 may be supplied by means of wires 21, extending through a hole 18', and connector plug 22 of well-known character (Fig. 1).

To the lower ends of the side members 18 55 are pivoted, by means of horizontal alining pins 23, the side members 24 of a swinging

frame, the connecting or transverse member of which, 25, carries the die or seal 26. The pins 23 extend through suitable slots in the standards 11. The slot in the left-hand standard in Fig. 1 is a simple vertical slot, but the slot in the other standard is of a special type, as will be explained below, said slot having a vertical portion 27 in which the corresponding pin 23 moves 60 between the extreme positions indicated in Figs. 2 and 3 respectively. About midway between its top and its bottom, the vertical slot 27 communicates with a curved branch slot 28 in which is adapted to travel at 70 times, a pin 29 projected outwardly from the adjacent side member 24. The upper portion of the slot 27 communicates either with the branch slot 28 (Fig. 2) or with the lower portion of the said vertical slot 75 27 (Fig. 3) according to the position of a dog or switch 30 pivoted to said standard 11 at 31. At the same point is also pivoted a sector 32 having two notches 32' adapted to be engaged by the end of a retaining 80 pawl 33 pivoted to said standard 11 at 34. A spring 35 presses the pawl 33 toward the sector 32, and another spring 36, coiled around the pivot 31, has its respective ends secured to the switch 30 and to the sector 85 32 respectively, so as to tend to hold them in a definite position relatively to each other, yet allowing the switch to yield while the sector remains undisturbed, under certain conditions explained below. A protecting 90 housing 37 may be provided for said switch and sector.

To the standard 11 is further pivoted at 38, to swing about a transverse horizontal axis, a bail or support 39 the central portion 95 of which forms an axle on which is mounted a moistening roller 40, of suitable absorbent material. This roller is shown located above an opening formed between extensions or feet 10" of the base 10. A spring 41 extending through one end of the bail 39 and coiled around a stationary pin 42, tends to throw the roller 40 into the lower or inner position shown in Figs. 2 and 4.

The sealing wax receptacle 19 has its lower portion contracted in funnel fashion, and its outlet is controlled by a valve 43, located within the receptacle and movable vertically. For this purpose, the valve is secured to a rod 44, guided in a flange 19' of said receptacle, and connected at the top with a rod 45 movable vertically in guides 18" on one

of the side members 18. The lower end of the rod 45 is provided with a cam portion 45'; eccentric to the pivot axis 23 (see Fig. 5) and extending with a sliding fit through 5 a horizontal pin 46 which is secured to the adjacent side member 24, at a distance from the pivot 23, in such a manner that said pin 46 may turn about its own horizontal axis, relatively to said member 24.

10 Finally, a spring 47, coiled around the rod 13 engages the upper washer 15 referred to above, and a similar lower washer 48 resting on the top member 12, said spring tending to raise the receptacle 19 and the other vertically movable parts to the normal position shown in Figs. 1, 2, 4 and 5.

15 The operation is as follows:

The receptacle 19 is supplied with sealing wax, which is kept molten by the electric heater 20. The sealing device and the article to which the seal is to be applied having been brought to the proper relative position and the parts being in the normal position shown in Figs. 1, 2, 4, 5, 6 and 7, the handle 20 14 is pressed down to the position illustrated by Fig. 3. This of course brings the receptacle 19 down together with its carrier. During this movement, the pin 29 on the die-carrying frame travels first in the vertical slot 27, but is soon deflected into the lateral branch slot 28 by the switch 30 which at that time projects across the vertical slot. While thus moving in the lateral slot 28, the pin 29 strikes the upper end of the sector 32 25 and forcing it aside, swings said sector and the switch 30 to the position shown in Fig. 3, so that the pin 23 may continue its straight downward travel to the position shown in Fig. 3. The notches 32' are of such a shape 30 that the pawl 33 will not lock the sector 32 positively, but will simply prevent accidental movement, said pawl yielding when the pin 29 causes the sector 32 to swing on its pivot 31. The travel of the pin 29 in the 35 slot 28 causes the die-carrying frame to swing on the pivot 23, the die 26 being thus carried into contact with the moistening roller 40, and sweeping past such roller which thus moistens the entire surface of 40 the die, the roller swinging to the position shown in Fig. 3, against the tension of the spring 41. The swinging of the die-carrying frame thus brings the die 26 from its normal position which is directly below the 45 outlet of the receptacle 19 (Fig. 4) to a side-wise position (Fig. 3) and at this time the valve 43 is opened by the lifting action of the pin 46 (as it swings about the center 23) on the cam portion 45' of the rod 45. Sealing wax will therefore pour out of the receptacle 19 and through the base opening 10' on the article below. When the amount of wax delivered is deemed sufficient, the operator releases the handle 14, and the spring 50 47 brings the receptacle 19 back to the upper

position, the pins 23 traveling upward in their vertical guide slots, and the pin 29 traveling to the right (Fig. 3) in the slot 28, and then up in the slot 27, to the position shown in Fig. 2. During this return 70 movement, the pin 29 engages the switch 30 and swings it aside from the position shown in Fig. 3; but as soon as the pin 29 has cleared the switch, the spring 36 restores the switch 30 to the position shown in Fig. 3. 75 The return movement of the pin 29 causes the frame carrying the die 26 to swing back to its normal vertical position, and the co-operation of the pin 46 with the cam portion 45' causes the valve 43 to be closed during this return movement. The device is then again in the position illustrated by Figs. 1, 2, 4, 5, 6, and 7, except that the sector 32, spring 36, and switch 30 remain in the position illustrated by Fig. 3. 80

85 The operator then again presses the handle 14 downward, carrying the receptacle 19 down as before. The pin 29 however, instead of entering the lateral branch slot 28, will on this second down stroke travel straight 90 down in the vertical slot 27. The frame carrying the die 26 will therefore have no swinging movement, but the die 26 will be carried down to make an impression on the blob of sealing wax previously deposited. 95 The valve 43 of course remains closed, owing to the fact that there is no swinging movement of the die-carrying frame. During its downward movement, the pin 29 comes in contact with the lower or right-hand end of the sector 32, which end at that time projects into the path of the vertical travel of the said pin. At the moment the pin 29 thus engages the said end of the sector 32, the upper pin 23 has descended in the slot 27 sufficiently 100 to be below the upper end of the switch 30. The further downward movement of the pin 29 swings the sector 32 back into the position shown in Fig. 2, the spring 36 yielding to allow the switch 30 to remain in the position shown in Fig. 3, since the pin 23 in its lower position prevents said switch from swinging to the right. The pressure of the pawl 33 against the inclined faces of the notches 32' will cause the sector 32 to snap 105 into either of its end positions. The operator then again releases the handle 14, and all the parts return to the position shown in Figs. 1, 2, 4, 5, 6 and 7, the spring 36 throwing the switch 30 into the position 110 illustrated by Fig. 2, as soon as the pin 29 in its upward movement clears the said switch. 115

I claim as my invention:

120 1. A device of the class described, comprising a frame, a receptacle movable up and down relatively to said frame, a valve controlling the outlet of said receptacle, a die connected with said receptacle movably, and means whereby one downward move- 125 130

- ment of the receptacle will cause the valve to open and the die to move aside, while the next downward movement of the receptacle will cause the die to press on the material previously delivered from the receptacle, the valve remaining closed during such second downward movement.
2. A device of the class described, comprising a frame, a receptacle movable up and down relatively to said frame, a valve controlling the outlet of said receptacle, a die-carrying frame connected with said receptacle and mounted to swing relatively thereto about a horizontal axis, and means whereby one downward movement of the receptacle will cause the valve to open and the swinging frame to carry the die aside, while the next downward movement of the receptacle will cause the die to press on the material previously delivered from the receptacle, the valve remaining closed during such second downward movement of the receptacle.
3. A device of the class described, comprising a frame provided with an upright slot and with a branch slot extending from a point between the ends of said upright slot, a receptacle movable up and down relatively to said frame and provided with a pin arranged to travel in said upright slot, a movable switch located at the junction of the two slots, to connect the upper portion of the upright slot either with the lower portion thereof or with said branch slot, a swinging frame connected with said receptacle and mounted to swing relatively thereto about a horizontal axis, said swinging frame having a pin adapted to travel either exclusively in the upright slot, or partly in the branch slot, according to the position of the switch, a die carried by said swinging frame and adapted to occupy a position either beneath the outlet of the receptacle or to one side thereof, a valve controlling said outlet and operated by the swinging movement of said die-carrying frame, and means, operated by said swinging frame, for causing the position of the switch to be reversed at each downward movement of the receptacle.
4. A device of the class described, comprising a frame provided with an upright slot and with a branch slot extending from a point between the ends of said upright slot, a receptacle movable up and down relatively to said frame and provided with a pin arranged to travel in said upright slot, a movable switch located at the junction of the two slots, to connect the upper portion of the upright slot either with the lower portion thereof or with said branch slot, a swinging frame connected with said receptacle and mounted to swing relatively thereto about a horizontal axis, said swinging frame having a pin adapted to travel either exclusively in the upright slot, or partly in the branch slot, according to the position of the switch, a die carried by said swinging frame and adapted to occupy a position either beneath the outlet of the receptacle or to one side thereof, a valve controlling said outlet and operated by the swinging movement of said die-carrying frame, and means, operated by said swinging frame, for causing the position of the switch to be reversed at each downward movement of the receptacle.
5. A device of the class described, comprising a frame, a receptacle movable up and down relatively to said frame, a valve controlling the outlet of said receptacle, a die connected with said receptacle movably, and means whereby one downward movement of the receptacle will cause the valve to open and the die to move aside, while the next downward movement of the receptacle will cause the die to press on the material previously delivered from the receptacle, the valve remaining closed during such second downward movement, and moistening means with which the die comes in contact when moved aside.
6. A device of the class described, comprising a frame, a receptacle movable up and down relatively to said frame, a valve controlling the outlet of said receptacle, and means, operated by the movement of the receptacle, for opening said valve during the downward movement of the receptacle, as the latter approaches the article on which the material delivered from the receptacle is to be deposited.
7. A device of the class described, comprising a frame having two standards and a top member, a carrier of U-shape movable up and down within said frame and provided with a handle, a spring tending to move said carrier upward, a receptacle secured to said carrier, a swinging frame pivoted to the lower end of the carrier, a die secured to said swinging frame, a valve controlling the outlet of said receptacle, and means whereby one downward movement of the receptacle will cause the valve to open and the die to move aside, while the next downward movement of the receptacle will cause the die to press on the material previously delivered from the receptacle, the valve remaining closed during such second downward movement.

CHARLES BARRETT.
